ABSTRACT

In a feed mechanism for pilger rolling mills, having a mandrel rod coupled to a piston of a liquid brake, cooperating with a brake chamber. The compressed liquid in the chamber acts upon one side of a differential piston acted upon on its other side by a pressure force that persists beyond the instant of reversal of the mandrel rod.

**FEED MECHANISM FOR ROLLING MILL OF THE
PILGER TYPE**

The present invention relates to the feed mechanism for a rolling mill of the pilger type. More particularly, the invention relates to the construction of a liquid brake included in the feed mechanism of a pilger type rolling mill. The feed mechanism in such a mill has the task of returning the work piece, i.e. the hollow bloom or billet, to a starting position, after disengagement from the pilger rolls at the end of a rolling stroke or step. The next rolling stroke, of course, works another section of the same billet. The entire rolling process involves several alternating rolling and return strokes.

The brake in this device is to brake the return motion of the feed mechanism to obtain a controlled stop. Basically, the return of the feed mechanism to the starting position for the next rolling step is an "unproductive" operation and should be carried out in the shortest possible time. Generally, it is deemed necessary that the feed mechanism, together with the billet, is at rest at the beginning of the next roll cycle. Investigations on pilger type rolling mills have led to the belief and conclusion that the acceleration of the feed mechanism by means of the rolls, as they rotate at a particular working speed, is responsible for progressively accumulating torsional distortion in the drive shafts or spindles and in the respective coupling and clutch elements. This cumulative distortion is deemed responsible for frequent breakage of such parts. Thus, excessive loading of the rolls and of its drive elements at the beginning of a roll stroke or cycle is to be avoided.

The present invention is based on the principle that, prior to engagement of the billet by the rolls, the feed mechanism is to be accelerated so as to assume, at least approximately, a linear speed that corresponds to the peripheral speed of the rolls at the point of engagement. The so-called spring feed mechanism, as used in the past, have attempted this type of approach, but they were operated without damping and that, in turn, led to vibrations within the feed mechanism, severely disturbing the entire operation.

The feed mechanism usually has a pneumatically operated piston and cylinder arrangement to provide for the return motion of mandrel and billet. Some of the known feed mechanism are provided with air brakes, others employ liquid brakes. In the liquid brakes the piston has a front end that enters a funnel-shaped brake cylinder filled with braking fluid. Braking fluid is displaced, to leave the brake chamber, e.g., through a ring-gap between piston and chamber wall. Alternatively, the brake cylinder is provided with a bore governed by a pressure limiting valve, to control bleeding off displaced braking fluid into a reservoir. In either case, kinetic energy of the feed mechanism is destroyed during braking. Particularly, kinetic energy is not stored for purposes of accelerating the equipment in opposite direction. The known constructions are not capable of providing for such storage.

Air brakes operate in that the feed mechanism compresses air during its return stroke. The compression brakes the masses but the pressure is limited by means of the safety valve. For proper adjustment of the valve the feed mechanism does, in fact, stop in the proper position at the end of the return stroke.

The present invention intends to improve particularly a feed mechanism for a rolling mill of the pilger type and, as stated, refers particularly to improvement of the liquid brake for such a feed mechanism. In addition, it may be assumed conveniently that the feed mechanism is pneumatically operated. The liquid brake is comprised of a braking piston and of a funnel-shaped braking cylinder with an exit opening for escape of displaced liquid during braking. It is unimportant for practicing the invention whether or not the funnel-shaped braking chamber is widened for establishing a ring-gap along the piston or whether the braking funnel merges into a cylindrical portion, so that the braking chamber piston is sealed by the piston. However, the amount of liquid that is permitted to escape at all from the brake cylinder in this conventional manner should be limited as liquid displacement is utilized otherwise.

It is a particular feature of the invention that the braking chamber is connected to act on the small surface of a freely displaceable, differential piston. The differential piston has a larger, low pressure surface, acted upon by a counter or balancing force which is maintained until the rolls re-engage the billet for the next rolling stroke. The combination of a balancing differential piston with a liquid brake in communication therewith, establishes a strongly damped system; the masses can be accelerated by operation of the counter force as acting upon the differential piston, but only once per rolling cycle stroke, the acceleration being effective opposite to the direction of motion during the return stroke and braking. The equipment will not oscillate about a starting position of the mandrel-piston arrangement.

15 The counter force, as referred to above, may be exerted upon the differential piston by a particular quantity of air which is contained in the auxiliary cylinder. This particular quantity of air is compressed during braking, but expands during acceleration of the feed mechanism in the reverse and moves the differential piston accordingly. It should be noted that differential pressure piston is displaced by the relatively incompressible liquid in the braking chamber acting on the small surface of the differential piston, while the relatively 20 highly compressible air on the other, low pressure side of the differential piston, will be sufficiently compressed to set up a reverse accelerating force upon expansion.

25 Alternatively, the counter force does not have to be build-up during braking of the feed mechanism but may be applied externally. For example, the auxiliary piston chamber is connected to the particular source of air pressure source that feeds the air cylinder of the feed mechanism for obtaining the return stroke thereof. Practicing the invention in this manner was found to be of particular advantage as the counter force 30 remains constant during braking as well as during acceleration of the feed mechanism in the reverse so that, in fact, the reversal of motion can take place in the shortest possible time.

35 The stroke of the differential piston may be limited so that the duration of effectiveness of the counter force is limited accordingly. For example, after the differential piston has reversed, it may soon engage a cross wall, stopper plate or the like within the differential piston cylinder, so as to terminate further acceleration for the mandrel rod. Thus, a definitely ascertainable quantity of stored energy is available due to the 40 particular construction in accordance with the present invention, which energy is available particularly for accelerating the feed mechanism in the reverse so that the rolls engage the billet on the mandrel when moving in the same direction. The operation can, therefor, readily be analyzed; fast operating servo valve mechanism or the like are not needed.

45 It should be pointed out that a particular starting position for the billet, in which the feed mechanism is at rest at the beginning of the next rolling stroke, is not really established. The feed mechanism merely halts momentarily upon reversal of motion because the counter force in the brake persists to obtain instantaneous reversal of motion of the mandrel and re-acceleration, unidirectional with the motion of the rolls.

50 Means are provided to indicate engagement of the billet by the rolls and/or which indicate the position of the billet relative to the phase angle of the rolls. Actually, the engagement is a particular relative phase position of rolls and billet. These means may not only include transducers to ascertain and to provide particular representation of interest, but they also 55 may provide control signals which operate the feed mechanism or the carriage on which the feed mechanism is advanced, so as to control (in time) the point where the rolls engage the moving billet. In other words, the phase of return motion of the billet is controlled so that for the given parameters, such as speed of the rolls, the span to the pilger rolled in the next rolling stroke is determined, through appropriate phase timing of the reengagement of the billet by the rolls.

56 While the specification concludes with claims particularly pointing out and distinctly claiming the subject matter which is regarded as the invention, it is believed that the invention,

the objects and features of the invention and further objects, features and advantages thereof will be better understood from the following description taken in connection with the accompanying drawings in which:

The FIGURE is a cross section through the braking and control mechanism for the feed equipment in a pilger rolling mill.

The stand of the pilger rolling mill is generally denoted with reference numeral 3. Reference No. 4 denotes the operating rod for the feed mechanism which is linked to the mandrel supporting the hollow bloom or billet to be pilger rolled. Though, frequently rod 4 is constructed to be disconnectible from the mandrel, it will be termed mandrel rod, as it is connected to mandrel and billet thereon during the particular operating phases of the invention. The mandrel as well as components 3 and 4 pertain to known types of feed mechanism that do not require elaboration. The same is true as to billet and rolls in the stand 3.

A cylinder 1 is part of the feed mechanism carriage, and is disposed for receiving a piston 2 reciprocating in a piston chamber 5 thereof. During pilger rolling, and here particularly during a rolling stroke, piston 2 moves to the right in the drawing, whereas the return motion of the feed mechanism is carried out to the left, towards rolling stand 3. A carriage advance is superimposed upon the return motion of the feed mechanism.

The motion to the right is imposed upon elements 2 and 4 by means of the rotating pilger rolls as acting upon the billet and, thereby, upon the feed mechanism for displacing rod 4 to the right. The axles of the pilger rolls, of course, remain stationary in relation to the system. The return motion for the feed mechanism to the left has piston 2 move under the influence of air pressure acting in cylinder chamber 5 connected to a source 18 of air pressure via an air conduit 7. The source 18 of pressure may be controlled to pressurize chamber 5 for obtaining the return motion of piston 2 (and of the billet after disengagement from the rolls). During a rolling stroke, pipe 7 is shut-off from source 18. Reference numeral 17 denotes the twist spindle of the feed mechanism.

As stated, during the return stroke air pressure in chamber 5 forces piston 2 to the left. In order to provide braking during the return of the feed mechanism a water brake is provided comprised of a funnel-shaped braking cylinder 6 coaxing with a head 16 of piston having configuration of a trunk-acted cone. The funnel-shaped brake cylinder 6 is provided with one or more exit openings 9 which communicate with an auxiliary cylinder 10.

A differential piston 11 reciprocates freely within cylinder 10. The differential piston 11 has a first, relatively small piston surface 12, acted upon by the braking fluid as is permitted to enter auxiliary piston chamber 10' via duct or ducts 9 upon displacement from chamber 6 by the piston 2. The oppositely effective, relatively large second piston surface 13 of differential piston 11 is acted upon by pressure of air in auxiliary chamber 10''. A cross wall 20 limits the stroke of differential piston 11 when piston 2 is moved to the right by operation of the air pressure in chamber 10'' as acting upon piston surface 13 for reversal of motion of mandrel rod 4 and of other parts of the feed mechanism. Air pressure for chamber 10'' is provided by the same source 18, via a pipe 7'.

An adjustable valve 14 is provided in a pipeline 15, which connects braking chamber 6 with a fluid tank such as water reservoir 8. The dashed line in tank 8 denotes the water level therein. Valve 14 is used only during the first few operating strokes upon rolling a new hollow billet. The valve is constructed so that braking fluid, i.e., water, can be sucked from the tank 8 into the braking chamber, the suction being produced by piston 2. During the return stroke the braking force is limited accordingly. Flow of braking fluid through pipe 15 is completely blocked by means of valve 14 during subsequent pilger steps, so that the braking force is determined exclusively by the balance of forces acting upon differential piston 11.

As it can be seen, during regular operation piston 2 is moved to the left to return the billet, mandrel and mandrel rod for engagement of the billet with the pilger rolls in the next rolling stroke. The return motion is induced by opening chamber 5 to air pressure from source 18 (there may be a valve in pipe 7). The motion is impeded as piston head 16 enters chamber 6 and tends to compress the water in chamber 6, thereby causing the water to be displaced. The displaced water shifts piston 11 so that balance with pressure force acting on piston surface 13 is maintained. As piston 2 slows down and stops, pressure force, as acting on 13, persists, so that piston 2 reverses and accelerates the mandrel rod 4 so that upon reengagement of the billet by the rolls they move at approximately similar speed.

Chamber 5 may have to be vented and line 7 is turned off during braking to terminate the pneumatic driving of piston 2 (to the left) prior to inducement of reversal by operation of the differential piston. Pressure on surface 13 should persist as that persistence induces the reversal and should remain operative in this manner at least until piston plate having surface 13 stops and sits on cross wall 20. Also, during this acceleration phase, as piston 2 moves to the right, the piston should not have to work against operating pressure in chamber 5. Pipes 7 and 7' may be governed by separate valves so that the operating air pressure acts on differential piston 11 longer than on piston 2. Actually, chamber 10' of the differential piston does not have to be disconnected from source 18 at any time as wall 20 restricts the motion of piston 11. Thus, a valve may not be needed in line 7'.

Transducers 22 are provided to ascertain the relative position of rolls and billet, possibly ascertaining also the instant of engagement. The output signals may be used to control, for example, the timing of actuating the valve control for pressurizing chamber 5 and/or to control a carriage drive 21 that advances the feed mechanism as a whole. Considering, that the rolls rotate at constant speed, the relative phase of feed mechanism, carriage advance and return of rod 4 etc. on the one hand, and of the rolls on the other hand, determines the point of re-engagement between rolls and billet. That point, in turn, determines the span or axial section of the billet to be rolled next. Thus, upon properly phasing the return motion of feed mechanism and billet, re-engagement of rolls and billet can be carried out while the billet is in motion.

A second embodiment can be regarded as being included in the figure. Assuming pipe 7' is eliminated and chamber 10'' is closed, that chamber is an air cushion that is compressed to some extent during braking, but expands as soon as piston 2 has stopped.

The invention is not limited to the embodiments described above but all changes and modifications thereof not constituting departures from the spirit and scope of the invention are intended to be included.

I claim

1. In a feed mechanism for rolling mills of the pilger variety, which includes a liquid brake and an air cylinder for operating movable parts of the feed mechanism, e.g., mandrel of the pilger roll, the brake including a piston connected to the mandrel supporting the billet to be pilger rolled, the piston cooperating with a funnel-shaped, water filled brake chamber, thereby establishing pressure in the chamber, the improvement comprising:

first means defining an auxiliary cylinder; a differential piston disposed for reciprocation in the cylinder and having first and second oppositely effective piston surfaces; second means for connecting the brake chamber to the cylinder for the pressure of the liquid in the brake chamber to act on the first piston surface of the differential piston; third means for providing a pressure force to act on the second larger piston surface; and fourth means connected for operating the third means for obtaining the pressure force and sustaining the latter

force until the pilger rolls re-engage the billet, so that the piston is accelerated in the reverse prior to the return cycle of the feed mechanism.

2. In a feed mechanism as in claim 1, the second differential piston surface being larger than the first surface, the pressure force being provided by air acting on the second surface.

3. In a feed mechanism as in claim 2, the auxiliary cylinder being closed, the air in the resulting chamber being compressed by operation of the second surface of the differential piston, the compressed air providing the second force.

4. In a feed mechanism as in claim 2, there being a source of

pressure for operating the air cylinder, said source connected to said auxiliary piston for the pressure to act on the second surface of the differential piston.

5. In a feed mechanism as in claim 1, there being means for limiting the stroke of the differential piston.

6. In a feed mechanism as in claim 1, there being means to ascertain relative position of the rolls and billet to provide control of the phase of reversal of motion of the piston relative to the instant of re-engagement of rolls and billet, after a 10 return stroke.
